UNITED STATES PATENT OFFICE

135,634

DESIGN FOR AN ELBOW PIPE FITTING

Julian E. Stark, Wilmette, and Edward G. Schmidt, Chicago, Ill., assignors to Crane Co., Chicago, Ill., a corporation of Illinois

Application December 21, 1942, Serial No. 109,090

Term of patent 14 years

To all whom it may concern:

Be it known that we, Julian E. Stark and Edward G. Schmidt, citizens of the United States, residing at Wilmette and Chicago, in the county of Cook and State of Illinois, respectively, have invented a new, original, and ornamental Design for an Elbow Pipe Fitting, of which the following is a specification, reference being had to the accompanying drawing forming part thereof.

Fig. 1 is a side elevational view of an elbow pipe fitting showing our new design.

Fig. 2 is a back view thereof.

Fig. 3 is a perspective view of the fitting.

We claim:

The ornamental design for an elbow pipe fitting, substantially as shown.

JULIAN E. STARK.
EDWARD G. SCHMIDT.
